CLAIM

The ornamental design for a pair of shoe soles, as shown and described.

DESCRIPTION

FIG. 1 is a left perspective view of the right odd of a pair of shoe soles, showing our new design;

FIG. 2 is a right side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof;

FIG. 8 is a left side elevational view thereof; and,

FIG. 9 is a perspective view of the pair of shoe soles in the position of use, showing our new design; the broken lines showing the shoe uppers illustrate the environment in which the design resides. The broken lines do not form any part of the claim.
